UNITED STATES PATENT OFFICE.

LOUIS HERRMAN AND JOHN B. LAVIN, OF BOSTON, MASSACHUSETTS,
ASSIGNORS TO THEMSELVES AND LOUIS JOSEPH HERRMAN.

CAR-COUPING.

SPECIFICATION forming part of Letters Patent No. 278,014, dated May 22, 1883.

Application filed March 29, 1883. (No model.)

To all whom it may concern:

Be it known that we, LOUIS HERRMAN and JOHN BRENNAN LAVIN, of Boston, in the county of Suffolk, State of Massachusetts, have invented a certain new and useful Improvement in Car-Couplers, of which the following is a description, sufficiently full, clear, and exact to enable persons skilled in the art or science to which said invention appertains to make and use the same, reference being had to the accompanying drawings, forming a part of this specification, in which—

Figure 1 is an isometrical perspective view, representing a car provided with our improved coupler; Fig. 2, a side elevation, showing the coupling-tongues detached; and Fig. 3, a view showing the coupler in use.

Like letters of reference indicate corresponding parts in the different figures of the drawings.

Our invention relates to that class of car-couplers which are automatic or self-coupling; and it consists in a novel construction and arrangement of the parts, as hereinafter more fully set forth and claimed, by which a simpler, cheaper, and more effective device of this character is produced than is now in ordinary use.

The nature and operation of the improvement will be readily understood by all conversant with such matters from the following explanation, its extreme simplicity rendering an elaborate description unnecessary.

In the drawings, A B represent the cars; C D, the draw-bar heads, and G H the coupling-tongues. The draw-bars are provided with springs at their inner ends, and are secured to the car in the usual manner. The coupling-tongues G H are precisely alike in construction, each consisting of an elongated flat bar pivoted at its inner end in the draw-bar head, as shown at x, and having its outer or free end wedge-shaped or tapering to a thin edge, as best seen in Fig. 2. Near the outer end of the tongue G there is an elongated slot, a, the tongue H being provided with a corresponding slot, d. Projecting from the upper side of each of the tongues there is a stud, m, having its outer side, l, inclined, and its inner side, n, at right angles to the plane of the

tongue. A straight stud, g, projects from the lower side of each of the tongues, the lower ends of these studs being beveled or inclined, as shown at f, to enable them to pass readily into position for use, as hereinafter described. 55

Pivoted at t to the forward end of the car A there is a vertically-arranged lever, E. This lever extends above the top of the car, and is jointed at its lower end to the bell-crank lever J by the link, v, this lever being also pivoted 60 to the forward end of the car, as seen at z.

A bell-crank lever, K, is pivoted at i to the upper side of the draw-bar head, one arm of this lever being connected by the link r to the lever J, and the other by the link w to the 65 tongue between the stud m and pivot x, as shown in Fig. 1.

As the car B is provided with corresponding levers, E J K, arranged and connected in precisely the same manner, it is not deemed 70 essential to describe the same.

In the use of our improvement, the levers E being arranged as shown in Fig. 1, or so as to permit both tongues to drop to their fullest extent, the cars A B are backed or run together, 75 causing the outer or free ends of the tongues to come into contact, and one to override the other, as shown in Fig. 2. As the cars continue to approach, the point of the upper tongue will strike and ride up the inclined face l of 80 the stud m, on the lower tongue, until the stud g on the lower side of the upper tongue falls into the slot in the lower tongue, and the stud m on the upper side of the lower tongue enters the slot in the upper tongue, thereby interlocking the tongues and coupling the cars in a manner which will be readily obvious without a more explicit description. 85

In Fig. 2 the tongue G is represented as uppermost, and when the tongues are coupled 90 its stud g will be in the slot d, and the stud m of the lower tongue in the slot a. In Fig. 3, G is represented as the lower tongue, the stud g of the tongue H being in the slot a, and the stud m of the tongue G in the slot d. The 95 studs g, working, respectively, in the slots a d, act as stops to prevent the cars from coming into contact when coupled. The strain in drawing the cars is exerted on the downwardly-projecting stud g of the upper tongue, which 100

takes the place of the ordinary coupling-pin, the principal office of the inclined upper studs, *m*, being to lift the tongues in the act of coupling, as described. It will be obvious, however, that in case the lower stud, *g*, of the upper tongue breaks, the upper stud, *m*, of the lower tongue will prevent the cars from uncoupling, thereby serving a double purpose, and preventing a class of accidents which frequently occur where ordinary couplings are used.

In uncoupling the cars the upper tongue is detached from the lower one by the brakeman on the car pushing the lever *E*, with which it is connected, toward the center of the car until the studs *m g* are withdrawn from their respective slots. The lever may also be operated and the cars uncoupled from the ground, if desired, without going between them, by means of the rod *M*, attached to the lower end of the lever.

Having thus explained our invention, what we claim is—

1. In a car-coupler, the pivoted tongue *G*,

provided with the stud *m*, stud *g*, and slot *a*, and the pivoted tongue *H*, provided with the stud *m*, stud *g*, and slot *d*, all constructed, combined, and arranged to operate substantially as set forth:

2. In a car-coupler, the pivoted levers *E J K* and tongue *G*, in combination with suitable means for connecting the same, when arranged to operate substantially as set forth.

3. The lever *M*, in combination with the lever *E*, to enable the cars to be uncoupled from the ground, or without going between them, substantially as described.

4. In a car-coupler, the tongue *G*, having the slot *a*, stud *g*, and stud *m*, and the tongue *H*, having the slot *d*, stud *g*, and stud *m*, in combination with the draw-bar heads *C D* and means for uncoupling the cars, substantially as specified.

LOUIS HERRMAN.

JOHN BRENNAN LAVIN.
